GAUMONT, OF PARIS, FRANCE.

MEANS FOR SYNCHRONOUSLY DISPLAYING CINEMATOGRAPHIC PICTURES AND REPRODUCING SOUND.

1,144,389.

Specification of Letters Patent. Patented June 22, 1915.

Application filed January 4, 1907. Serial No. 350,857.

To all whom it may concern:

Be it known that I, LÉON GAUMONT, a citizen of the French Republic, and a resident of Paris, Isle-de-France, France, have invented certain Improvements in Means for Synchronously Displaying Cinematographic Pictures and Reproducing Sound, of which the following is a specification.

This invention relates to certain improvements in cinematographic apparatuses, and more particularly in that class of such apparatuses which are especially designed and adapted for employment in connection with simultaneously actuated phonographs, or equivalent accompanying instruments, and the object of the invention is to provide an apparatus of this general character of a simple and comparatively inexpensive nature having novel and improved means for facilitating the operation of the cinematograph in substantially synchronous relation to the operation of the phonograph or equivalent accompanying instrument, so that accompanying words or music may be produced by such phonograph in properly timed relation to the motion pictures produced by the cinematograph.

The invention consists in an apparatus of this general character including two mechanisms, one of which is a phonograph or talking machine, and the other of which is a cinematograph or moving picture machine adapted to be operated in unison with the operation of said phonograph, or vice versa, and an index means controlled from the operation of one of said mechanisms and serving as a means to facilitate the control of the other mechanism.

The invention consists in certain novel features of the construction, and combinations and arrangements of the several parts of the improved cinematographic apparatus, whereby certain important advantages are attained, and the apparatus is rendered simpler, less expensive and otherwise better adapted and more convenient for use, all as will be hereinafter fully set forth.

The novel features of the invention will be carefully defined in the claims.

In order that my improvements may be the better understood, I will now proceed to describe the invention with reference to the accompanying drawings, wherein—

Figure 1 is a front elevation of an appa-

ratus embodying my improvements; Fig. 2 is a rear elevation of the apparatus as shown in Fig. 1; Fig. 3 is a vertical section taken centrally through the apparatus shown in the preceding figures; Fig. 4 is a vertical section taken transversely through the apparatus in a plane at right angles to the plane of the section in Fig. 3; Fig. 5 is a plan view showing a modified formation of the improved cinematographic apparatus comprised in my present invention; Fig. 6 is a sectional view taken vertically through the apparatus shown in Fig. 5, the plane of the section being indicated by the line $\alpha-\alpha$ in said figure, and Fig. 7 is a view somewhat similar to Fig. 1, but illustrating still another formation of the improved cinematographic apparatus comprised in my present invention.

Referring first to Figs. 1 to 4, the apparatus is therein shown mounted upon a support or table 1 of any preferred nature, and is provided with a frame or casing comprising end plates 2, 2 formed from insulating material, and spaced apart from each other to receive between them at their upper parts a tubular metal shell or sleeve 3, the ends of which are shown as being sunk in the faces of the insulating end pieces 2, 2 as indicated at 4 in the drawings.

The shell or sleeve 3 may be conveniently formed from soft iron so as to be adapted to support within its interior a plurality of pole pieces 5, 5 whereon field windings are supported, there being a shaft 6 extended axially through the shell or sleeve with its ends journaled in the end pieces 2, 2 and with its intermediate part provided with a rotor 7 arranged in relation to the pole pieces so as to constitute an electric motor. 8, 8 represent commutator rings mounted on the shaft 6 and adapted to connect the armature windings in circuit with brushes 9, contacting with said rings 8, 8 in a well known way.

One end of the shaft 6 is extended into a recess at the rear surface of the rear end piece 2, and has fixed upon it a gear wheel 10, meshing with an intermediate gear wheel 11 mounted to turn upon a stud 12, and meshing in turn with a gear wheel 14 secured upon the rear end of a stud or shaft 15 which is directed forwardly into the space between the end pieces 2, 2 below the

shell or sleeve 3, and has a bearing at the rear end of the frame or box 16 of a differential gear device, the said frame or box 16 being arranged in the lower part of the space between the insulating end pieces 2, 2 below the sleeve or shell 3, and having at its opposite ends forwardly and rearwardly directed trunnions or bosses 17, 17 which are journaled in said end pieces 2, 2 as clearly seen in Fig. 3. The stud or shaft 15 as herein shown, is extended axially through the rearwardly directed boss or trunnion 17 of said box or casing.

Within the box or casing 16 the stud or shaft 15 carries fixed upon it a bevel gear wheel or member 18 which is in mesh at its opposite sides with intermediate bevel gear wheels or pinions 19, 19 held upon a transverse shaft or stud 20 extended across said box or casing 16 at right angles to the length of shaft 15, and at the forward part of said box or casing, said intermediate gear wheels or pinions 19, 19 are in mesh with a bevel gear wheel 21 similar and opposite to the gear wheel 18, and held upon a shaft 22, alined axially with said shaft 15 and mounted to turn in a bearing produced axially within the forwardly directed boss or trunnion 17 of the differential gear box or casing 16, with its forward end extended in front of said boss or trunnion and provided with a gear wheel 23. 24 represents a spur gear wheel or pinion supported to turn upon a bracket 26 adjustably held as seen at 27 upon the table or support 1 and in mesh with the gear wheel 23, and being operatively connected with a flexible shaft or equivalent driving connection as seen at 25.

The forward extremity of the forwardly directed boss or trunnion 17 of the box or casing 16 of the differential gear device is formed into a pinion 28 which is in mesh with a spur gear wheel 29, having a boss 30 mounted to turn freely upon a stud 31 extended from the front plate 2, said boss 30 having fixed upon it an index member or pointer 32 adapted, during the movement of the parts, to play over a gage member 33 carried by the front plate 2 as and for purposes to be hereinafter more particularly explained.

In carrying out my invention in connection with the parts constructed and arranged as above described I provide a phonograph and a cinematograph of any preferred description, one of which mechanisms, as for example, the phonograph, has an electrical distributer, or other equivalent means, electrically connected to the motor 60 adjacent the differential gearing, adapted to operate said motor synchronously, or in a certain time relation to the turn-table or cylinder support of the phonograph. Said motor, which runs synchronously with the phonograph, has a shaft 6 which is in op-

erative connection with the driven shaft 15 at the rear end of the differential gear device, while the other mechanism, or cinematograph, is operatively connected with the shaft or connection 25 in such a manner that motion is communicated from such cinematograph to the gear wheel or pinion 24, which is thus driven from the cinematograph and serves to communicate the movement thereof to the forward shaft 22 of the differential gear device.

In the practical operation of the apparatus constructed and arranged as above described it is evident that if the gearing for driving the shaft 22 of the differential gear device from the cinematograph be proportioned properly with respect to the ratio desired to be maintained between the phonograph and cinematograph, so that the alined shafts 15 and 22 of the differential gear device are driven at equal speeds, no movement will be communicated to the box or casing 16 of the differential gear device, and consequently the pointer or index member 32 will remain substantially stationary in a central or neutral position with respect to the gage member 33, but if either the cinematograph or phonograph be driven at an excessive speed, a corresponding movement of the box or casing 16 of the differential gear device will ensue, causing the index member or pointer 32 to play over the gage member 33 in one direction or the other dependent upon which of the two mechanisms has the excessive speed, and indicating to the operator a required increase or diminution of the speed of either the cinematograph or phonograph such as is needful to insure a properly timed relation between them.

By replacing the gear wheels 23 and 24 with other wheels or different relative dimensions, it is evident that the apparatus may be accommodated for use in connection with phonographs and cinematographs which are to be uniformly driven at different relative speeds. Where interchange of these wheels is desirable, the adjustable connection of bracket 26 with the table or support 1 permits such interchange to be readily accomplished, and the flexible shaft 25 permits the mechanism connected therewith to be adjusted into any desired position relative to the mechanism which is coupled with the shaft 15 of the differential gear device.

By the operation of the apparatus as above described, the attendant is permitted, by observation of the index member or pointer 32, to so vary the speed either of the phonograph or cinematograph as may be necessary to maintain a substantially constant timed relation between the two mechanisms. The actual control of the speed of the phonograph or cinematograph may be accomplished in any desired man-

105

110

115

125

130

ner, and I have not deemed it necessary to illustrate any special means for this purpose in the drawings.

From the above description of my improvements, it will be seen that the apparatus constructed according to my invention is of an extremely simple and comparatively inexpensive nature, and is particularly well adapted for use by reason of the convenience and facility with which the desired timed relation may be maintained between the phonograph and cinematograph, and it will also be obvious from the above description that the apparatus is susceptible of considerable modification without material departure from the principles and spirit of the invention as defined in the appended claims, and for this reason I do not desire to be understood as limiting myself to the precise formation and arrangement of the several parts of the apparatus shown herein in carrying out my invention in practice. Nor do I desire to be understood as limiting myself to the employment of my improvements in connection with any special form or kind of motor or driven means operating in time relation with the phonograph or cinematograph, since it will be evident that the special nature of such motors or driven means is altogether immaterial to my present invention. For example, in some cases, the construction of the apparatus shown in Figs. 5 and 6 may be employed with good results. As shown in these figures, 34 represents an electric or other motor suitably mounted and connected with a source of energy which may be a battery or the like, and provided with a shaft 35 supported in bearings 36 and provided with a grooved wheel 37 adapted to receive a belt or band from which may be driven a phonograph in connection with which a cinematograph is desired to be operated. 38 represents the frame or casing of a differential gear device, the shaft 35 being extended in a bearing at one side of said frame or casing, and carrying a miter gear wheel 39 with opposite sides of which mesh intermediate gears 40, 40 turning on aligned axes 50 at right angles to the length of shaft 35, and meshing, at the side of the frame or casing opposite to said shaft 35, with opposite sides of a miter gear wheel 41 secured upon a shaft 42 which has a bearing in frame or casing 38 and is extended therefrom opposite to and in alignment with the shaft 35 and is supported in suitable bearings 43. 44 represents spur gears by means of which the shaft 42 is operatively connected with the shaft 45 of the cinematograph 46 in connection with which the phonograph is used, said cinematograph being herein shown as provided with a crank handle 47 by means of which it may be manually driven in a well known way.

One of the bearings 36 for the shaft 35 is provided with a stationary gage member 48, and the end of the casing or frame 38 of the differential gear device which is adjacent to such bearing is provided with a pointer or index member 49 which in the operation of the parts is adapted to play across or stand stationary and centrally positioned with respect to the gage member 48 of the bearing 36 in such a manner as to indicate to the attendant at all times the speed relation existing between the phonograph and cinematograph, so that the speed at which the crank handle 47 is turned may be varied by the attendant to maintain a proper timed relation between such mechanisms. The operation of the apparatus constructed as above described is substantially similar to that shown in Figs. 1 to 4, inclusive, excepting that the attendant exerts control over the speed of the cinematograph through the crank handle 47 in order to maintain a substantially constant timed relation between the phonograph and cinematograph and to prevent excessive fluctuation of the index member 49 relative to the gage device.

In Fig. 7 I have shown another modified formation of the improved cinematographic apparatus wherein the front plate 2 carries insulated contacts 50, 50 which, when the index member or pointer 32 is moved in one or the other direction from its central or neutral position, are adapted to communicate electrically therewith to close one or the other of two electric circuits 51, 51 each of which includes a generator 52. Signals or alarms are also included in the respective circuits so as to be operated upon closure thereof to give warning of deviations from the desired speed ratio of the phonograph and cinematograph. Such signals or alarms may be in the form of differently colored incandescent lamps 53, 53, differently pitched bells 54, 54, or other audible or visible devices.

Having thus described my invention, what I claim and desire to secure by Letters Patent is—

1. Means for synchronously displaying cinematographic pictures and reproducing sound, comprising a cinematograph and a phonograph adapted to be located remote one from the other, an indicating device, said indicating device comprising a differential gearing, an electric motor adjacent said differential gearing for driving one of the gears thereof, electrical means under the control of a moving part of, and adapted to rotate said motor at a speed having a definite time relation to, the remote one of said cinematograph and said phonograph, a connection between the second gear of said differential and the other of said phonograph and said cinematograph, and an indi- 130

cator hand actuated by the intermediate gear of said differential.

2. Means for synchronously displaying cinematographic pictures and reproducing sound, comprising a cinematograph and a phonograph adapted to be located remote one from the other, a differential gearing, an electric motor adapted to drive one of the gears of said differential, electrical means under the control of a moving part of said phonograph for driving said motor at a speed having a definite time relation to said phonograph, a connection between the other gear of said differential and said cinematograph, and an index actuated by the intermediate gear of said differential, said index being adapted to maintain a fixed position when the definite time relation between the phonograph and cinematograph is maintained, and to indicate by its movement to one side or the other a deviation from the definite time relation of said cinematograph and phonograph.

3. Means for synchronously displaying cinematographic pictures and reproducing sound, comprising a cinematograph and a phonograph adapted to be located remote one from the other, an indicating device comprising a frame, a differential gearing mounted in said frame, an electric motor also mounted in said frame and adapted to drive one of the gears of said differential, electrical means under the control of a moving part of said phonograph for driving said motor at a speed having a definite time relation to said phonograph, a connection between the other gear of said differential and said cinematograph, and an index actuated by the intermediate gear of said differential, said index being adapted to maintain a fixed position when the definite time relation between the phonograph and cinematograph is maintained, and to indicate by its movement to one side or the other a deviation from the definite time relation of said cinematograph and phonograph.

4. Means for synchronously displaying cinematographic pictures and reproducing sound, comprising a cinematograph and a phonograph adapted to be located remote one from the other, a differential gearing, an electric motor adapted to drive one of

the gears of said differential, electrical means under the control of a moving part of said phonograph for driving said motor at a speed having a definite time relation to said phonograph, a connection between the other gear of said differential and said cinematograph, and an index actuated by the intermediate gear of said differential, said index being adapted to maintain a fixed position when the definite time relation between the phonograph and cinematograph is maintained, and to indicate by its movement to one side or the other a deviation from the definite time relation of said cinematograph and phonograph, said motor and said cinematograph being connected to the respective gears of the differential through intermediate gears which are adapted to be changed to obtain a desired speed relation between said phonograph and motor.

5. Means for synchronously displaying cinematographic pictures and reproducing sound, comprising a cinematograph and a phonograph adapted to be located remote one from the other, a differential gearing, an electric motor adapted to drive one of the gears of said differential, electrical means under control of a moving part of said phonograph for driving said motor at a speed having a definite time relation to said phonograph, a connection between the other gear of said differential and said cinematograph, and an index actuated by the intermediate gear of said differential, said index being adapted to maintain a fixed position when the definite time relation between the phonograph and cinematograph is maintained, and to indicate by its movement to one side or the other a deviation from the definite time relation of said cinematograph and phonograph, electrical signaling devices, and contacts at each side of said index, said index being adapted to actuate said signaling devices upon coming into contact with said contacts.

In witness whereof, I have hereunto signed my name in the presence of two subscribing witnesses.

LÉON GAUMONT.
